UNITED STATES PATENT OFFICE

HERMAN L. FELDBLET, OF NEW YORK, N. Y.

FORM AND FORM HOLDER FOR CONCRETE WALL AND ARCH CONSTRUCTION

Application filed June 6, 1928, Serial No. 283,181. Renewed September 6, 1930.

This invention relates to forms and form holders for constructing specified concrete walls and arches under varying conditions so that the wall thickness at the arch is always the required value regardless of the depth of the column or that of the sustaining beam.

Another object includes the provision of simple but inexpensive standard forms for jack arches and means for supporting said forms at varying depths.

A further object includes the provision of a simple and efficient form holding device having means for temporarily anchoring said device to a column or girder member at varying depths, to thereby support the arch forms at a fixed distance from the outer wall surface, or of the floor, of the finished wall or arch.

The forms and form holders are intended primarily for the construction of concrete side walls and roof of subways. The section of both side wall and roof consists of an arch of specified depth or thickness and held between steel columns, or beams. It so happens that in the case of the side walls, on account of the fact that the columns vary in depth as well as in flange width, it is necessary to provide form holders with adjustable features both longitudinally and in depth to thus provide against these variations and I accomplish these objects by my construction shown herein.

Aside from the adjustment feature which is incorporated specifically in the bolts and associated parts, the clamps, which are a part of the form holders, serve to attach the holders to the columns and eventually transfer the load entailed by pouring wet concrete back of the form work to the column, thus eliminating the necessity of exterior bracing to hold the forms in position. Longitudinal adjustment, which is necessary on account of variable flange width of column, is taken care of by lapping the outstanding leg of the form holder over the core portion of the form which is inserted between the holders. Once the holders are attached to the columns and the core is inserted between said holders, the longitudinal variation in width is automatically taken care of.

For roof construction the same principles apply excepting that the wet concrete load may be transferred to the clamps, which are an integral part of the form holders, or the concrete load may be carried partially on the form holders and partly by a fixed or movable support under the core portion of the form assembly.

Other objects will appear hereinafter and I obtain these objects by the construction illustrated in the accompanying drawings in which

Figure 1 is a sectional view of a concrete wall or ceiling showing my improved form and form holders still in position in one of the arches.

Fig. 2 is a plan view of the construction shown in Fig. 1 viewed from the arched side.

Fig. 3 is an enlarged sectional view of the concrete form and form holding device.

Fig. 4 is a plan view looking down on the construction of Fig. 3.

Fig. 5 is a view substantially on the line 5—5 of Fig. 3.

Fig. 6 is a partial plan view of the construction shown in Fig. 5.

Fig. 7 is a view in perspective showing my new form holder attached to the flange of a column or girder.

Fig. 8 is a face view of the form holder of Fig. 7 without the column or girder and showing an adjacent form holder.

Fig. 9 is a view in perspective of two sections of forms and adjacent girders with my form holders applied thereto.

Fig. 10 is a side elevation showing adjacent form holders, and

Fig. 11 is a view from line 11—11 of Fig. 10 looking in the direction of the arrows.

Like numerals refer to similar parts throughout the several views.

In constructing concrete walls for subways and the like, it has heretofore been the practice to use standard forms for the arches between definitely placed H-columns having substantially uniform webs, thereby providing for walls of required thickness. With the use, however, of columns of varying dimensions and forms of standard width it is not possible to build the walls of the re-

quired thickness. To meet this difficulty I have devised adjustable form holders and special form constructions whereby walls of the required thickness may be built under varying conditions.

As a specific application of my invention I have illustrated, in Fig. 1, a sectional view of concrete wall construction 10, in which my new form holders 11 and concrete forms 12 are employed to obtain an arched wall, or floor, of specified thickness x with no waste of concrete.

It is evident that if the given thickness x of the concrete wall, or floor, is to be a constant factor for a given wall, or floor, and that if the web h of the columns 13 varies that provision must be made to meet this variation in depth, my new adjustable form holder 11 provides means to meet these conditions as will presently appear more fully. The over-hanging leg m of said form holder provides also means for compensating for variations in the flange n of the column or girder 13, as appears clearly in Fig. 3.

A preferred type of form holder 11 comprises a trough shaped member of sheet metal, or other suitable material, having an arched over-hanging leg m , a side wall w and bottom o . A reinforcement plate p at either end of holder 11, and if desired also at a midway position is provided to strengthen the holder. Near either end is the adjustable clamp member 20 having jaws 21 and 22 extending through a slot in wall w to engage the flange n of the column or girder. The clamp may be held at varying positions on the flange by a set screw 23. At suitable positions on the arched member m and the bottom o there is screwed a screw threaded bolt 24 having a nut 25 between the loosely fitting fingers 26 and 27 of clamp 20. It will be noted that by adjusting nut 25 the form holder is adjusted in order to properly hold form 12 for the required thickness of the wall 10. (Fig. 1) or roof (not indicated in Fig. 9).

On the bottom of the form holders 11 I provide brackets 31 to receive form supporting bars 32. These bars may be angle irons and are dropped into position when forms 12 have been placed into position.

The concrete supporting forms 12 may be of suitable length and of standard width to fit between the form holders. Any mode of construction, such as wood frame covered by metal roof 34 and supported or held in position by blocks 35 resting on the form supporting bars 32 will serve the purpose. In the roof form of Fig. 9 for example, the concrete supporting form 40 may be supported from the form holders 11, or the weight may be carried on frame 41, which if necessary or desirable may be supported on a movable support as a car or other means (not shown). It is understood that any desired number of form holders may be clamped end to end on

the column or girder and the required number of forms are supported therefrom to fill in the height of the wall, or the length of the roof arch, and that the concrete holding forms are adjusted by said holders to the proper position so as to provide walls (or the roof arches) of the specified thickness, regardless of the depth of the web or the width of the flange of the column or girder.

While I have shown and described preferred forms of construction for the application of my invention, I do not thereby desire to be understood as having thus limited myself as various modifications falling wholly within the spirit and scope of my invention will suggest themselves to those versed in the art.

What I claim therefore as new and useful and desire to secure by Letters Patent is:

1. In concrete construction the combination of concrete supporting forms of substantially similar dimensions and clamping members having an arched roof to connect with said forms and vertically movable clamping means having clamping jaws to engage the flange of a column or girder and means for varying the positions of said clamping jaws.

2. In concrete construction the combination of concrete supporting forms of substantially similar dimensions and clamping members having an arched roof to connect with said forms and vertically movable clamping means having clamping jaws to engage the flange of a column or girder and means for positioning said forms at a required depth.

3. A form holder for supporting concrete forms at a specified depth comprising a trough like member with a floor and a side wall having slots therethrough, clamping means extending through said wall, and means in said trough for varying the position of said clamping means in said slot.

4. A form holder for supporting concrete forms at a specified depth comprising a trough like member with a floor and a side wall having slots therethrough the upper side of said trough being free to overhang said floor, clamping jaws extending from said slot, and means in said trough for adjusting the position of said clamping jaws.

5. A form holder for supporting concrete forms at a specified depth comprising a trough like member with a floor, a side wall and an overhanging arch to engage concrete forms at varying positions, flange engaging means adjustably carried by said trough member, and brackets on the bottom of said trough like member for holding form supporting bars.

6. In a form holder for supporting concrete forms at varying positions from the flange of a column or girder, a trough like member having roof and bottom and a screw

threaded bolt secured thereon, a nut on said bolt and clamping means having fingers on said bolt on either side of said nut for holding said form holder at desired positions.

⁵ In testimony whereof I have hereunto set my hand on this 22nd day of May, A. D. 1928.

HERMAN L. FELDBLET.
